DESIGN FOR A POWDER PUFF

Evangeline Burkhart, New York, N. Y.

Application March 5, 1935, Serial No. 55,734

Term of patent 14 years

To all whom it may concern:

Be it known that I, Evangeline Burkhart, a citizen of the United States, residing in the Borough of Manhattan, county of New York, and State of New York, have invented a new, original, and ornamental Design for a Powder Puff, of which the following is a specification, reference being had to the accompanying drawing, forming part thereof.

Fig. 1 is a front view of a powder puff showing my design; and

Fig. 2 is a sectional view thereof taken along the line 2—2 of Fig. 1 looking in the direction of the arrows.

I claim:

The ornamental design for a powder puff as shown.

EVANGELINE BURKHART.
